PAGE 2

FIG-3

FIG-4

FIG-5

FIG-6

FIG-7

FIG-8

FIG. 1 is a top plan view of a toy vehicle trackway showing my new design;

FIG. 2 is a bottom plan view;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a perspective view thereof, showing the state in which the toy vehicle trackway section is extended; and

FIG. 8 is a cross-sectional view taken along the line X—X of FIG. 1.

I claim:

The ornamental design for a toy vehicle trackway, as shown.
